UNITED STATES PATENT OFFICE.

HENRY A. HARTSHORN, OF WEST HAVEN, CONNECTICUT, ASSIGNOR TO THE AMERICAN BUCKLE CO., OF WEST HAVEN, CONNECTICUT, A CORPORATION.

OVERALLS-SUSPENDERS LOOP.

1,266,590.

Specification of Letters Patent. Patented May 21, 1918.

Application filed January 12, 1918. Serial No. 211,485.

To all whom it may concern:

Be it known that I, HENRY A. HARTSHORN, a citizen of the United States, residing at West Haven, in the county of New Haven and State of Connecticut, have invented a new and useful Improvement in Overalls-Suspenders Loops; and I do hereby declare the following, when taken in connection with the accompanying drawings and the characters of reference marked thereon, to be a full, clear, and exact description of the same, and which said drawings constitute part of this application, and represent, in—

Figure 1 a face view of a loop for overalls suspenders constructed in accordance with my invention, and shown in connection with a suspender strap and button.

Fig. 2 a front view of the device, detached.

Fig. 3 a side view of the same.

Fig. 4 a front view of a modified form of my invention.

Fig. 5 a side view of the same.

This invention relates to an improvement in overalls suspenders loops adapted to be attached to the lower ends of suspenders on overalls to engage with buttons on the bib or apron, and particularly to loops formed in two parts, a loop proper and a button-engaging member suspended from the bottom of the loop, the object of the invention being a simple means of connecting the button-engaging member with a loop to provide for movement of the loop independent of the button engaging member, and to provide stops to limit the swinging movement of the button-engaging member; and the invention consists in the construction hereinafter described and particularly recited in the claims.

In carrying out my invention, I employ a loop-member 6 formed from a single piece of wire bent to form an elongated eye 7 which is engaged with the suspender web 8 in the usual manner. The ends 9 and 10 of the wire are curved to form spring limbs the extreme ends 11 and 12 of which are flattened and bent to form eyes 13 and 14, the wires above the eyes being bent inward to form a contracted throat 15. The button-engaging member 16 is also formed from

a single piece of wire formed in its center with a dip 17, the ends 18 being turned toward each other and passing through the eyes 13 and 14, the ends 19 and 20 being turned upward, and preferably of such a length as to engage with the lower ends of the loop member so as to limit the swinging movement of the button-engaging member, as clearly shown in Figs. 1 and 2 of the drawings, although, as shown in Fig. 4 of the drawings, the ends of the button-engaging member may be cut off so as to clear the loop-member but provide stops 21 and 22. This button-engaging member engages with a button 23 attached to bibs or aprons of overalls, the upper portion of the loop-member being wider than the distance between the outsides of the loop eyes 13 and 14 is of sufficient size to freely pass over the button which is crowded down through the neck 15 into the button-engaging member, and by providing the button-engaging member with the inwardly turned ends 11 and 12 provision is made for the springing movement of the loop-member independent of the button-engaging member, so that the device may be used with a button having a comparatively large shank which may be crowded through the throat 15 without difficulty as the ends of the loop freely move with relation to the button-engaging member. If the button-engaging member is formed with the stop-fingers 19 and 20, the button-engaging member is limited in its movement so that it is held in a comparatively rigid position to facilitate the engagement with the button. With this construction the loop-member and button-engaging member are readily formed in automatic machines and easily assembled.

I claim:—

1. A loop for overalls suspenders comprising a loop member formed with a contracted throat the ends of the member below the throat formed with transversely arranged eyes, combined with a button-engaging member wider than the lower end of the loop member the end portions of which are turned inward through the said eyes and terminating in stops.

100

2. A loop for overalls suspenders comprising a loop-member the ends of which are provided with eyes, combined with a button-engaging member the ends of which are turned inward through the said eyes and turned upward into the path of the sides of the loop-member.
